UNITED STATES PATENT OFFICE.

GEORGE H. CROWELL, OF BERLIN, NEW HAMPSHIRE.

ELECTRIC STEAM GENERATOR.

Application filed April 15, 1925. Serial No. 23,411.

My invention has for its object to provide a new apparatus for the generation of steam for heating systems, etc., and it particularly has for its object to provide a heater or steam generator of a simple and inexpensive construction in which the parts are self-contained and of such design and arrangement that the electric heater-unit will be immersed in the coldest part of the water; all the water supplied in such a way as to surround the packing on the water supply valve; the water will flow directly from the inlet chamber adjacent the inlet valve to the section of the housing which contains the heating unit, thus maintaining a fairly low and even temperature at these two places so as to avoid burning of these two parts (the inlet valve packing and the electric heating coil) ensuring long life to the whole apparatus.

Another object of my invention is to provide a housing of approximately L-shape with the steam dome at the top and the heating unit in the lower horizontal section, the housing being provided with a globular chamber intermediately located and provided with a detachable horizontal section constituting the float chamber and water inlet control chamber, making it possible to have an extremely low water line, thus making it also possible to use the apparatus for sterilizers, vulcanizers, pressing, laboratory work and all other purposes for which steam is employed where the generator is on approximately the same level and adjacent to the machine in which the steam is used.

With other objects in view, the invention includes those novel details of construction, combination and arrangement of parts, all of which will be first fully described, then be pointed out in the appended claims, and illustrated in the accompanying drawing, in which:

Figure 1 is a side elevation of the invention.

Figure 2 is an end elevation of the same. Figure 3 is an enlarged detail central vertical longitudinal section through the inlet valve.

Figure 4 is a section on the line 4—4 of Figure 1 looking in the direction of the arrow.

In the drawing, in which like numerals of reference indicate like parts in all of the figures, 1 represents the housing which is in the form of an L-shape body having an enlarged globular section 2 intermediate the vertical

part of the body and a domed top 3 which carries the steam gauge 4 and safety valve 5 and which is provided with the steam outlet 6. The construction of the safety valve and the steam gauge may be that of the ordinary kind, as the same, per se, forms no part of the present invention.

7 is a flange formed on the housing in line with the globular portion 2 to which is bolted the flange 8 of a horizontal extension chamber 9 that preferably tapers down from the flange 8 toward the outer end and adjacent to the outer end it is bored and tapped at 10 for the reception of the water inlet valve hereinafter again referred to.

A short distance back from the water inlet valve opening 10 is a baffle 11 and adjacent to the baffle and between it and the opening 10 there is another opening 12 bored and tapped to receive the duct 13 which conveys the cold water to the inlet 14 to which the return flow pipe of the heating system is tapped to be connected in the usual way.

16 is a water level gauge glass connected to the housing with cutoff valves 17—17, at either end of the same.

The lower arm of the housing 1 is provided with legs 18—18 which support the apparatus with the lower part of the housing inclined downwardly toward the end which has a flange 19 and which is adapted to receive the heating unit. The heating unit consists of one or more heating coils 20 mounted on a cap 21 (from which they are insulated in any suitable way), the cap 21 being adapted to be bolted to the flange 19, as shown. 22 designates the water inlet valve body which is threaded at 23 to fit in to the threaded opening 10, the body having a suitable nut flange 24 and a packing ring 25 being interposed between that flange and the extension housing 9. 26 is the valve seat member which is insertable into the bottom of the valve body 22 and has a flange 27 between which and the lower end of the body 22 is a packing 28, another packing 29 being interposed between the flange 27 and the flange 30 of a nipple 31, the parts 31, 29, 27 and 28 being adapted to be held in place in water-tight connection by means of the flange nut 32 that is screwed on to the lower threaded end 33 of the body 22.

34 is the valve proper which is of an elongated body having two grooves 35 and carrying at its lower end a valve disk 36.

that is adapted to seat on the valve seat end 37 of the valve seat member 26 to shut off the inflow of water, it being understood that the cold water supply from a suitable source 5 (not shown) is connectable to the nipple 31.

The valve body 34 has an eye 38 into which the heel 39 of the float lever 40 projects, the lever 40 being fulcrumed on a rod 41 suitably mounted in the housing extension 9, the float 42 of the float lever lying in the globular enlargement 2 of the housing.

In practical operation, the apparatus is set up in a vertical position on its feet with the water supply pipe connected from the source 15 of supply to the nipple 31, and suitable circuit wires are connected to the terminals of the heating units 20 to energize the same, it being understood that any suitable switching device may be employed whereby one or 20 more of the units may be brought into circuit as desired, but as such forms no part of the present invention a disclosure thereof is thought to be unnecessary. Water will flow through the water inlet valve up around the 25 valve proper 34 and spill over the top of the valve casing 22, running down the bottom floor of the extension 9 until it engages the baffle 11 and passes through the duct 13 to the lower extension of the housing, where 30 the electric heating units are located. When the water has reached its proper level the float 42, acting on the water inlet valve, will close off the inflow of fresh water and when electric current is admitted to the heating 35 units 20 the water is heated to the boiling point, generating steam which collects in the apparatus above the water line, and in the dome 3 ready for use. When the steam supply valve is opened and steam is being used 40 if the condensate is not returned from the return pipe that is connected to the return inlet to compensate for loss of water, then the float 42 drops, opening the valve 34, letting a very small quantity of water into the 45 hollow arm which flows until it strikes the baffle 11, which directs it down the pipe 13, maintaining a steady water level in the apparatus.

From the foregoing description it is 50 thought the complete construction, operation and advantages of the invention will be clear to those skilled in the art. It will also be seen that by my invention the expense of manufacture is reduced to the minimum and the parts can be readily assembled and disassembled for the purpose of repair or cleaning, if desired.

What I claim is:

1. In electric steam generators, a housing 60 having an upright portion and an approximately horizontal base portion, said upright portion having a steam dome at the top and a float chamber below the dome, a supplemental housing portion projecting 65 from the float chamber part of the upright

portion, a water inlet valve within said supplemental housing, a float lever mounted in said supplemental housing for operating said valve and a float on said lever located within said float chamber, a return flow 70 duct to said approximately horizontal base portion, a cold water duct from said supplemental housing to said return flow duct, substantially as shown and described.

2. In electric steam generators, a housing having an upright portion and an approximately horizontal base portion, said upright portion having a steam dome at the top and a float chamber below the dome, a supplemental housing portion projecting 80 from the float chamber part of the upright portion, a water inlet valve within said supplemental housing, a float lever mounted in said supplemental housing for operating said valve and a float on said lever located 85 within said float chamber, a return flow duct to said approximately horizontal base portion, a cold water duct from said supplemental housing to said return flow duct, and means for directing the water into said cold water duct.

3. In water heaters, an approximately L-shaped housing having a steam chamber at one end and a flanged opening at the other end, an electric heating body comprising a cap closing the flanged opening and carrying heating elements projecting into the housing; said housing having an intermediate chamber with a flanged opening, a supplemental housing closing said last named flanged opening, a water inlet valve to said supplemental housing and a water transfer pipe from said supplemental housing to the bottom of said L-shaped housing, a float lever in said intermediate chamber and said supplemental chamber to operate said valve, said L-shaped chamber having a steam outlet and a return flow inlet substantially shown and described.

4. In electric steam generators, a tubular approximately L-shaped housing having a vertical portion and a downwardly inclined approximately horizontal portion, a cap closing the end of said portion, electric heater elements carried by said cap and projected into said approximately horizontal portion, means maintaining said housing in position, a supplemental housing attached to said vertical portion and having a bottom inclined upwardly from said place of attachment, a water inlet at approximately the highest part in said supplemental housing, a float lever in said housings for operating said valve, a water duct from said supplemental housing adjacent said valve and leading to the lower end of said approximately horizontal portion of said L-shaped housing, said L-shaped housing having a steam outlet and a return flow inlet.

5. A steam generator comprising a tubu-

- lar L-shaped body having a vertical portion, an approximately horizontal portion, a chambered body secured to said vertical portion intermediate the ends thereof and in communication at one end with the L-shaped body, said bodies being in communication directly one with the other, electric heating elements in the approximately horizontal portion of said L-shaped body, a 10 fresh water inlet to such chambered body, a float controlled valve governing said inlet and means for directing and conveying the fresh water admitted to said chambered body downwardly to the outer end of said 15 approximately horizontal portion of said L-shaped body, substantially as shown and described.
6. A steam generator comprising a tubular L-shaped body having an approximately 20 horizontal base part, and means carried
- thereby for sustaining the body, an electric heating unit mounted within the bottom part of said L-shaped body, said L-shaped body having a steam dome at the top and a supplemental chambered body secured to the vertical 25 part of said L-shaped body below the steam dome, a float lever controlled water inlet valve in said supplemental chambered body, means for delivering water thereto, said float controlled valve including a tubular 30 valve chamber projected into said supplemental chambered body through which the incoming water overflows, a duct from said supplemental chambered body leading to the portion of said L-shaped body containing the heating elements, and a baffle wall in said supplemental chambered body for directing the cold water to said duct, substantially as shown and described.

GEORGE H. CROWELL.
